(57) **CLAIM**

The ornamental design for an alternator bracket, as shown and described.

DESCRIPTION

FIG. 1 is a first perspective view of a first design of an alternator bracket;

FIG. 2 is a second perspective view of the design of FIG. 1;

FIG. 3 is a front view of the design of FIG. 1;

FIG. 4 is a rear view of the design of FIG. 1;

FIG. 5 is a first side view of the design of FIG. 1;

FIG. 6 is a second side view of the design of FIG. 1;

FIG. 7 is a top view of the design of FIG. 1; and,

FIG. 8 is a bottom view of the design of FIG. 1.

The broken lines in the drawings illustrate portions of the alternator bracket which form no part of the claimed design.
